Budd Company, Philadelphia, Pa., a corpora-
tion of Pennsylvania

Application November 23, 1945, Serial No. 630,401

18 Claims. (Cl. 323—4)

1

This invention relates to electrical control systems and more particularly to systems which are dependent upon load change primarily for introducing a control sequence.

In the conventional electrical system where power is applied to a load it is common practice to employ, where a series of loads is involved, a timing mechanism during which power is applied to the load. In the use of the timer, indicating means are utilized which disclose when the timing period is over so that the load may be removed and a new load applied for a second or subsequent timing period. The timing period is in this type of use set at an average value which is at or in excess of the time necessary to supply the load, so that should through some special condition of the load this time be insufficient, nevertheless the indication of timer completion will occur, and if the load is removed it would be insufficiently treated. This arises from the fact that the timing is an arbitrary step in the method of treatment and is not related to the state of the load as indicating the normal completion of the treatment. Such considerations apply to a variety of material, manufacture and treatment, such as heating methods, welding methods, and the like.

Particularly in welding operations from the viewpoint of electrical efficiency, economy and time saving, it is of considerable importance that the time of power application be related to the period in which the weld actually takes place. Difficulties in accomplishment of this result are abundant, such as electrode pressure variations, chance current changes, variations in electrode contour, variations in contact resistance at the electrodes, and other factors.

Generally stated, an outstanding object of the present invention is to provide an improved electrical control system which functions on a change in the load condition indicating completion of the treatment. Another object of the invention is the provision of a control system in which improved current compensating means are employed to overcome changes in the voltage which are not related to the change of condition of the load itself. Still another object of the invention is to provide an improved form of circuit functioning as a comparator whereby an initial voltage comparable to the pre-change load voltage is established in a circuit and the diversion of the voltage from this pre-change voltage is registered in the apparatus and utilized as an operating means to bring about an indication of completion of load treatment, a disconnection of

2

the power source from the load, or any unrelated power actuation. A further object of the invention is to provide an improved form of load treatment completion indication utilizing both visual and graphic means. Additional objects are to provide measuring means for the differential between the fixed time and the actual time of load treatment; to provide a bridge circuit permitting use of vacuum electronic tubes; to provide control means for changing but not cancelling current flow in the power source; and to increase the normal speed of action of the circuit as described. Other objects of the invention will appear on further consideration of the specific details of the invention as applied to a form of the invention which may be preferred and hereinafter described and illustrated in the accompanying drawings, in which:

Figure 1 is a diagrammatic view of the electrical circuits and apparatus employed to accomplish the objects of the invention;

Figure 2 is a wiring diagram of the circuit applicable to the visual and graphic indicating means;

Figure 3 is a wiring diagram illustrative of a use of the invention modified from that of Figure 1; and

Figure 4 is a detail indicative of the graphic mechanism employed to indicate the completion of the load treatment.

The control system of this invention in its broadest conception is applicable in any circuit in which a load receives power from an electrical source either in one amount or shot or in a plurality of amounts or shots in sequence. It is, of course, also applicable to the supply of power to a series of loads in a continuous sequential treatment from a power source irrespective of the nature of the power. However, in order to make clear the usefulness of the development as associated with a specific type of load, the drawings of the application and the specific description both relate to an adaptation of the system to a resistance spot welding circuit wherein power is supplied in a series of continuing shots, each for a brief interval of time. To this end the circuit as illustrated may be divided into four sections: A, the power section including the welding transformer and the electrodes; B, the power control section; C, the weld controlled section; and, D (Fig. 2), the indicator section.

Taking up the mentioned sections of the circuit of Figure 1 as indicated above, section A, or the power section, includes a welding transformer 55 including a primary coil 2 and secondary coil

3 suitable for supplying the heavy currents necessary for welding purposes. The secondary 3 has direct connection to the electrodes 4 and 5 which are adapted to receive a workpiece, such as 6 in the form as illustrated, of two overlapping metal sheets disposed between the electrodes for welding. Power is supplied the primary 2 of the welding transformer from a source of alternating current indicated by the numeral 1, this power being directly controlled by a contactor 8 in the B section interposed in the transformer wiring with the primary coil terminals in series therewith. The contactor 8 takes the usual form now conventionally in use of inversely connected ignitrons 9, 10 adapted to transmit alternate half cycles of current from the source to the primary. These ignitrons are supplied with igniters 11 adapted for energization by the timing circuit formed of branches, generally indicated by the numerals 12, 13 and 14. This is a direct current circuit which includes a trigger tube 15 in branch 12, an auxiliary control tube 16 in branch 13, and direct thyratron control tubes 17 in branch 14. By means of the variable resistor 18 in branch 12 the number of cycles in which welding current is supplied to the workpiece is fixed so that by adjusting the value of this resistance the time period of current application to the load is properly controlled.

In addition to the time control this circuit also employs a heat control indicated generally by the numeral 19. This heat control, as shown, is in the form of a phase shift wherein by appropriate variation of a resistor 20 in the phase shift bridge the fraction of each half cycle of current which is applicable to the load circuit is determined. Voltage compensating means 21 is also indicated in parallel with the heat control branch circuit 19.

Various timing, heat and voltage controls as related to the power unit A are used conventionally by manufacturers of welding equipment and specifically do not enter into the invention. The operation of these controls appears in numerous publications, such as "Electronic Control of Resistance Welding" by George M. Chute, McGraw-Hill Publishing Company, and therefore will not be described in detail here. Mention should be made, however, of the following items in connection with this control circuit. Resistor 18 in branch 12 which controls the timing obviously is made ineffective by short-circuiting of the same as indicated by a conductor 25 so that by application of the short-circuiting conductor 25 the time of power application is reduced to a small amount. The voltage drop applicable to control tube 16 by means of which the power timing is attained may be nullified by opposing voltage drop applied across a resistor 26 in the branch circuit 13 by means of conductor 27 whereby the timing action of the control is made ineffective and the power supply cut off. The heat supply as controlled by the phase shift circuit 19 may be reduced to a small amount by short-circuiting a substantial section of the phase shift bridge resistor 20 through conductors 28 and 29. Conductor 30 in timing control branch 12 may be opened at will to deenergize the timing circuit. Each of these alternative deenergizing means may be employed by insertion in each of the conductors mentioned of relay switches, normally closed relay switch R1-1 being in series with conductor 30, normally open switch R1-2 being in series with conductor 25, normally open switch R1-3 being in series with conductor 27, and normally open

switch R1-4 being in series with conductors 28 and 29. Each of these relay switches is connected in fixed relation to a movable core 35 operable by the relay coil R1, as is also another normally open switch R1-5 later to be described. Selection of the appropriate deenergizing means is made by the short-circuiting manual switches 37 in each of the conductor circuits mentioned.

Mention should be made also of the initiating switch circuit 40 including the relay coil R2 effective on energization by closure of initiating switch 42 to close relay switch R2-1 adjacent the timing circuit section 12. Switch 42 may be either manual or, as is usually the case, automatic in the sense that a sequence circuit is effective to close and open the switch at recurrent, uniform intervals.

The circuits A and B as above described relate to a specific type of load and power control means appropriate for this load, as in a welding system. Description will now be given of control means in section C dependent upon the state of the load to bring about a power manifestation in the same or a separate circuit either to indicate a completion of load application visually or graphically or by actual interruption of the supply of power from the source of the load. Section C may be readily divided into rectifier, current compensating, comparator, percentage control and power units.

At points, preferably closely adjacent the electrode tips of the power circuit as described and illustrated in my copending application Serial No. 533,977, now Patent #2,433,827, January 6, 1948, filed May 3, 1944, conductor taps are made leading to the amplifying and rectifying circuit 50 including the transformer 51, the rectifying tube 52, and the filter circuit with the capacitors 54 and the choke coil 55. Tool inductive effects are neutralized by a variable inductor 49 adjacent the welding yoke circuit.

In addition, means are provided for lifting the level of the filtered voltage to overcome lag in arriving at the peak electrode voltage. As shown, the two filter conductors beyond the rectifier 52 and between the choke coil and transformer are connected through a rectifier 195 to the secondary of a transformer 196. The alternating current source 197 supplies power to the transformer 196 through variable resistor 199 and also to tube filament transformer 198.

The outlet points 56 and 57 are connected to a current compensating branch circuit, a resistance 58 being connected between the outlet points to slow down the discharge of the capacitors 54. This circuit includes a current transformer 58, forming part of the welding circuit secondary, an amplifying transformer 59, a bridge rectifier 60 between a tapped section of the secondary at point 190, and connections to the positive fixed point 61 and the potentiometer 62 establishing the negative terminal of the rectified circuit at point 48. Two vacuum tubes 63 and 64, 63 being a triode amplifier and 64 a pentode amplifier, are connected between points 61 and 48 of the current compensating circuit, and points 56 and 57 of the rectified weld-connected circuit as follows: 48 is connected to the cathode 65 and to the suppressor grid 69 of tube 64, 61 is connected through an opposing potential such as the battery 66, and also through a resistor 67 to the control grid 68 of tube 64. Point 56 of circuit 50 is connected to the outlet point 71 and point 57 is connected to the anode 70 of tube 63. In addition, the cathode 71 of tube 63 is connected through a resistor 72 to the anode 73 of tube 64. The cath-

ode 71 of tube 63 is connected to the screen grid 74 of tube 64. Control grid 75 of tube 63 is also connected to the anode 73 of tube 64. It appears by these connections that points 76 and 77 are established as the outlet points of the connections to the electrodes 4 and 5 after current compensation. A fixed voltage from a source of direct current 78 is applied across tube 64 to insure functioning within the linear characteristic of the $E_g - I_p$ curve.

The operation of the section of the C unit as hereinabove described follows: On receiving an alternating current impulse between the electrodes 4 and 5, the branch circuit 50 amplifies and rectifies the same and passes it into the compensating circuit at the tubes 63 and 64. Since the rectified potential from transformer 196 is derived from a constant independent source, the filter system is loaded by being charged to an elevated voltage and consequently the signal energy necessary to start the circuit sequence is greatly reduced. For example, if the operating peak be 350 volts and the operating range 300 to 350 volts, a maintenance of voltage at 275 volts eliminates the time for charging from zero to 275 volts. Thus the circuit responds properly to a short weld of one or two cycles as readily as to one of five or six cycles. If there is no variation in the secondary current, there will be no modification in this transmission, and the outlet points 76 and 77 will constitute points of uniform potential difference with the point 76 positive in relation to the point 77. During this condition the current transformer 58 transmits a voltage which is amplified and applied at points 61 and 48 as a constant potential difference, with the point 61 being positive in relation to 48. The value of the voltages at 61 and that due to the battery 66 are preferably selected so that possible voltage changes due to current variation come within the range of the selected voltages. In any event, the opposition of the voltages will reduce the voltage difference between the cathode 65 and control grid 68 of tube 64, permitting an increased flow of current through this tube. Should a variation of the current occur in the welding secondary, as, for example, a decrease in current, the result will be the development of an increased voltage at the cathode 65 due to the lessening of the opposing voltage 61, 48 as against the voltage of battery 66. Consequently, relative to the cathode, the bias voltage of control grid 68 reduces in value thereby decreasing the effective resistance of tube 64 to current passing therethrough from constant source 78 and thus causing a decrease in the negative bias of grid 75 in tube 63 and an increase of voltage as between points 76 and 77, the outlet points of the weld control circuit 50. In this manner compensation is made for current variation in the welding secondary circuit.

The third unit of the C section may be termed a comparator inasmuch as it establishes an initial voltage impressed thereon as a basis of comparison with a subsequent voltage of the circuit and through this difference of voltages the control or indicating sections of the circuit are energized.

The comparator unit includes a capacitor 101, which may be referred to as the memory circuit capacitor, connected to the positive point 82 of conductor 97 and through a rectifying tube 100 and variable resistor 80 to the point 81, points 82 and 81 corresponding to outlet points 76 and 77 respectively of the C section unit. Thus the capacitor is charged in proportion to the maximum

voltage occurring between points 81 and 82, which in turn are components of the load voltage. By adjusting the contact arm 83 of potentiometer 80, which may be referred to as the percentage resistor, and which is connected directly across points 81 and 82, the capacitor 101 may be charged to any desired percentage value of the load voltage component since the resistance of potentiometer 80 is uniform along the length.

10 Since the tube 100 transmits current in one direction only, there is no discharge of the capacitor through the tube. Hence, the maximum voltage impressed is retained subject to a controlled discharge through resistors 98 and 99 and a short-circuiting discharge through relay switch R2-2. This switch R2-2 is normally closed but is opened by the relay coil R2 of the initiating circuit 49 when the welding power is applied to the main circuit. It is the function of the control apparatus to translate the comparator voltage values as determined by the potentiometer 80 into percentage values of the voltage effective at the weld. This is accomplished by connecting to the percentage resistor, operating circuits which function on a change of potential from that initially established by the comparator to another potential equal to the percentage value which the points 81, 82 of the electrode potential may assume.

In order to effectuate this voltage change, use is made of a comparator bridge arrangement including the vacuum tubes 84 and 85 and the equal resistors 86 and 87 forming the four branches of the bridge. A relatively constant current supply is obtained from the source 88, the positive potential being applied between the resistors 86 and 87 and the negative potential being applied to the bridge through the contact 89 of a variable resistor 90. The function of the resistor 90 is to permit the bridge to be set with an initial negative bias from zero for the condition prior to application of the incoming voltage 81, 82. The purpose of this construction will appear in the following description.

Tubes 84, 85 of the bridge are of the same type, but when the potential of an incoming signal impulse is applied at points 81 and 82 the grids of the same are subject to different voltages. The grid 91 of tube 84 is connected to a voltage dividing circuit between points 81 and 82 including resistors 92 and 93 so that the point of connection 94 is substantially below in voltage than that of point 82. The grid 95 of tube 85 is connected to the comparator unit at a point 96 in a circuit including the conductor 97 and resistors 98 and 99, the ratio of the resistance of resistor 98 to resistor 99 being the same as that of resistor 93 to resistor 92. Accordingly, the resistances of these circuits are such preferably that the voltage of grids 91 and 95 are equal when the arm 83 of the percentage potentiometer 80 is at its upper or maximum voltage point. Consequently, under normal operation for a given percentage setting of the potentiometer 80, the effective resistance of tube 85 is less than that of tube 84 because the negative potential on grid 95 of tube 85 is less than that on grid 91 of tube 84. Since the resistances 86 and 87 of the bridge are the same, point 106 is maintained negative relative to point 105, thus unbalancing the bridge to maintain a power tube 108 inoperative. The potential at point 105 is applied to the cathode and one grid of tube 108 and the potential at point 106 is applied to another grid of the tube and the tube characteristics are such that it will fire when the bias of the tube grids reaches a pre-

determined relationship, as when the potentials at 105 and 106 are equal. With this condition of unbalance existing at the inception of the incoming signal, when the voltage drop on fusion at the weld occurs, the potential of grid 91 approaches the potential of grid 95 which is being maintained by the capacitor 101 at the peak voltage value, until at the point of approximate potential equality the bridge becomes balanced, the potential of point 108 becoming equal to or positive in relation to point 105, and the tube 108 strikes. Thus the cut-out or other power or indicating mechanism is energized.

The shift in balance of the bridge 84, 85, 86, 87 brought about by a change in potential at points 81, 82 is effective at bridge points 105 and 106. Prior to the change of potential the bridge balance is such that the cathode 107 of the gas tetrode 108 is, in relation to the control grid 109, at a value preventing energization of the tube. Assuming that the tube will strike and develop a current flow between the anode 110 and cathode 107 when the bridge is at or above zero balance in the positive sense, then the necessity of the unbalancing resistor 90 appears since by use of this resistor the actuation of tube 108 from the chance voltage variations is prevented. Since the shift of voltage due to the potential change at points 81, 82 is substantial, amounting to as much as 90 volts, it is apparent that the initial unbalancing of the bridge, as between 0.5 to 2.0 volts, by resistor 90 does not hinder the effectiveness of the bridge operation. Accordingly, when a voltage change occurs at 81, 82 the bridge is unbalanced in the positive sense reducing the negative bias of grid 109 and causing the tube 108 to strike thereby to energize coil R1 of the relay switch unit and bring about actuation of any one of the four circuit-modifying means hereinabove described. Power applicable to tube 108 and the series-connected coil R1 is derived from the constant potential source 111. The circuit of tube 108 includes also, in addition to relay coil R1, the time delay relay coil R3, a variable resistor 113, and a contact switch R2-3 operated by relay R2. A variable resistor 115 is connected in shunt with the time delay relay coil R3 to vary the time of relay energization in accordance with the tolerance desired. Also, conductor 21 of branch circuit 13 of the power control circuit B is connected in parallel with the tube and resistor 113, this circuit including the normally open relay switch R1-3 and the manual switch 31.

There is shown also in the circuit, cathode ray tuning indicators, as indicated by the numerals 120 and 121. The purpose of the indicator 120 is to establish an indication that the proper signal is supplied from the welding tool and also that a correct proportion of the developed voltage may be fed into the current compensator. To this end the tube 120 is connected across the constant potential source 88, and its grid 122 is connectible through the switch 191 to the slide arm 123 of the potentiometer 124. The potentiometer is connected across points 81 and 82 through a resistor 119. By adjustment of the potentiometer 124 the point indicating a proper signal at the tool may be secured as a preliminary adjustment. Also, the grid 122 is connectible by means of switch 191, potentiometer 192, and conductor 193 to the point 190 of the current compensator transformer secondary. This point is connected to a potentiometer slider arm 192a so that voltage variation as desired may be secured and made

effective at the tuning indicator. Thus adjustment of compensation for current variations due to workpiece thickness and the like is available.

Similarly, the tuning indicator 121 is used to secure a predetermined balance point for the bridge contact 89-90. The grid 125 of tube 121 has connection to the potentiometer 126 for this purpose. While helpful in facilitating adjustment, these cathode ray tuning indicators are not essential to the operation of the system.

In Figure 2 of the drawing there is illustrated a circuit which is used in connection with visual and graphic indicating means. This circuit consists primarily of three lamps 130, 131 and 132, having in parallel therewith respectively electromagnets 133, 134 and 135. Lamp 130 is green in light transmission, lamp 131 transmits an amber light, and 132 a red light. This indicating circuit is so adjusted that the amber light 131 is energized when the power is applied to the load, this light indicating initial supply of energy into the weld and being succeeded by the green light 130 when the load through a voltage change in the same brings about a voltage change in operation 25 of the load-control circuit. The green light is maintained until the normal time period ends as set by the timer or the initiating switch 42 opens, unless this time period is in excess of the time necessary for actuation of time delay coil R3 in 30 the circuit of tube 108. If the latter condition be the case, then the green light goes out and red light 132 becomes lighted, thus indicating that the set time of closure of the power circuit is in excess of the time required for securing a complete application of power to the load. It also indicates the presence of excessive energy in the weld, if the percentage dial has been correctly set. If this lighting sequence with the appearance of the red light continues, then adjustment may be 40 made so that the time or amount of power application may be reduced.

In order to make clear the operation of the indicator circuit of Figure 2, it is pointed out that the relay switches R2-4, R2-5 are closed coincident with the closure of initiating switch through functioning of the relay coil R2. On closure of relay switch R2-4 a circuit is immediately established through the amber light 131 and also through relay coil R4, whereby relay switch R4-1 locks in the coil to maintain light in lamp 131, alternating current power being supplied from source 200 and relay switch R2-6 being closed by initiating coil R2. As soon as the power becomes effective in the load and a change of voltage occurs therein sufficient to bring about the functioning of the load-control coil R1, this coil becomes operative to close relay contact switch R1-5 as well as the switches hereinbefore mentioned operative to interrupt the circuit of the power supply to the load. On closure of switch R1-5 green lamp 130 becomes lighted and at the same time relay coil R5 operates to lock in green lamp switch R5-1 and to open normally closed relay switch R5-2 in the amber light circuit. This condition maintains until the time delay relay R3 develops sufficient energy to close normally open relay switch R3-1, thereby lighting the red lamp 132 and energizing relay coil R6 to lock in switch R6-1 and to open normally closed switch R6-2 in the green lamp circuit and the normally closed switch R6-3 in the amber light circuit. It is apparent that the red lamp will not become lighted if switches R2-4 and R2-5 are opened due to end

of timer period or opening of switch 42 in the initiating circuit.

The electromagnets 133, 134 and 135 being connected in shunt with the lamps are of course energized coincidentally therewith. In order to secure a graphic record of control periods, in the present arrangement this is accomplished by means of these electromagnets in connection with movable armatures, inking pens, and a traveling paper roll. Reference is made to Figure 4 of the drawing for a diagrammatic showing of apparatus which is associated with the electromagnets 133, 134 and 135 to secure this record. As indicated, the armatures 148, 149 and 150 carry terminal pen points 151, 152 and 153 at one end and are pivoted in alignment at the other end. The pen points are adapted to engage paper 154 wrapped about a roll rotatable on the shaft 156 in the direction indicated. Suitable mechanism for controlling the movement of the drum, including power units and connections for rotation of the drum during the application of power to the load, is provided.

The operation of sections of the circuit has been indicated hereinabove, but it may be helpful to consider briefly the sequence of operation of the unit as a whole and as applied to resistance welding. Before starting the welding operation, the voltage sources including 7, 66, 78, 88, 111, 197 and the control source of direct current in the B section are applied to the circuit and the percentage resistor 80 and unbalancing resistor 98 adjusted by aid of the cathode ray indicators 120 and 121. Assuming the interposition of a workpiece or load as designated by the metal sheets 6 between the electrodes 4 and 5, power is applied for welding purposes by closure of switch 42 in the initiating circuit, this closure being either manual or automatic in the case of a sequence-operated system. Energization of relay coil R2 results in closure of switches in the indicating circuit as mentioned and also closure of normally open relay switch R2-3 in the power circuit of tube 108, relay switch R2-6 in the indicator circuit of Figure 2, and the relay switch R2-1 in the power control circuit thereby causing functioning of the timing circuit and the related heating and voltage control circuits, and resulting in the application of the welding current to the workpiece. The resistance of the workpiece is generally maintained until fusion occurs at the interface between the sheets, and in this time interval prior to fusion the comparator unit develops the initial maximum voltage effective at the weld point through the instrumentality of the capacitor 101. During this time interval, should there be a change in current, the compensator unit, 58, etc., corrects for this change.

In this initial time interval and before fusion at the weld point the amber lamp of the indicator is also energized, showing to the operator that current is being applied.

When the workpiece fuses at the interface, a continuing decrease in resistance at the weld results as the nugget enlarges accompanied by a drop of potential which is transmitted by the C circuit and made effective across the percentage resistor. At the proper point of time this drop brings about a strong unbalance of the bridge circuit in the direction necessary for actuation of the associated power circuits, whereupon power tube 108 is energized and relay R1 connected thereto is caused to function to operate its core 35 to open switch R1-1 of the power circuit and

to close its other switches including R1-5 to light the green lamp in the indicator panel, through R5 and R5-1, as well as shut off the amber lamp, through R5-2. This condition 5 maintains until the time delay switch coil R3 in the load power circuit operates to close switch R3-1 and through relay R6 and switch R6-1 to light the red lamp and, by relay R6 and switches R6-2 and R6-3 cut off the green lamp, and to 10 open a gap in the circuit of an amber lamp; or until the timer or initiating switch 42 opens.

The particular advantages of the circuit as described include the effective current compensation of the voltage as derived from the load 15 so that irrespective of fluctuations in current there is attained a voltage value which is dependent primarily only on voltage change at the load. Of outstanding importance in the circuit also as promoting practical operation of the 20 same is the utilization of the bridge in association with the comparator wherein vacuum tubes are employed. In balancing operations it has been found that greater evenness and uniformity and accuracy of balance can be secured utilizing 25 vacuum tubes as against tubes containing various atmospheres, and the described arrangement provides an effective circuit for use of vacuum tubes in this connection. The circuit also has outstanding merit in the facility in which not only 30 disconnection of a power source may be made as applied to the load, but in also providing other indications of load treatment completion, either visual or graphic. Observation should be made of the scope of the circuit, which is not restricted 35 to the cutting-out of a power source effective on the load of the same power source. Obviously the power circuit of the load-responsive means may be utilized for any other purpose, such as the making or breaking of a power circuit unrelated to the power source for the load of the circuit. Thus in its general scope the invention has to do with a control circuit which functions on a change of voltage current in the load and operates to actuate any associated power circuit either 40 for indication or cut-out or for other functions.

While the description as made hereinabove has for purposes of illustration been applied to a welding circuit in which operation of the load control is dependent upon a drop of potential in 45 the load circuit, obviously the load control may function on an increased voltage at the load point or at any other point comparable to the load point. In Figure 3 of the drawing I have indicated a circuit arrangement which may be applied to a load for operating a load control on increase of voltage at the load point. The points 160 and 161 correspond to points 81 and 82 of Figure 1, with point 161 positive in relation to point 160. The percentage resistor is indicated 50 by the numeral 162, but in this form of the disclosure the capacitor 163 is connected directly to the grid 164 of the vacuum tube 165 on the negative side of the circuit. Tube 165, in conjunction with vacuum tube 166 and associated resistors 167 and 168, form the branches of the bridge similarly as described in conjunction with Figure 1. Source 169 supplies power to the bridge at points 170 and 171, the connection at 171 to the bridge being through variable resistors 172 to effect initial unbalance of the bridge. The grid 173 of tube 166 is connected through a resistor 174 to the movable contact 175 of the percentage resistor 162. Also, the outlet terminals 176 and 177 of the bridge have connection to the cathode 55 178 and control grid 179, respectively, of gas power

tube 180 so that when the proper relation between grid and cathode is established the tube strikes and permits the transfer of power from the positive source point 181 through the tube to the negative point 182 of the source. Thereupon the potential drop of the circuit is utilized at terminals 183 for any desired power function.

The operation in this form of the system is dependent upon an increase in voltage across the terminals 160 and 161 to bring about a shift in the bridge balance to that side of the zero point which will permit operation of the power tube 180 in the operating circuit. Initially the source voltage is impressed upon the grid 164 of tube 165 and the capacitor 163 through the time delay switch 194. The capacitor 163 is thus charged to the impressed voltage and after one or two cycles the time delay switch operates to open the circuit, the capacitor then maintaining the voltage on the grid 164, pending voltage variation in the incoming current. On an increase of voltage from the source effective on the grid 173 of tube 166, this tube is brought to the balance point in a manner similar to that described in the principal form of the invention.

As described, the circuit is usable for seam welding if the signal is taken off the rollers near the point of weld.

Various detail modifications of the described circuit may be made. For example, the resistors 98 and 99 in the voltage fixing circuit may be omitted and capacitors substituted.

Other modifications of the invention may of course be made, the showing being diagrammatic and subject to rearrangement suitable for the desired loads and applications of the system. Hence no limitation is implied by the disclosure other than that which may be required by the claims as hereto appended.

What is claimed is:

1. In a system of power supply control including a power source and a load unit receiving power from said source and subject to voltage change, means for correcting the load voltage to compensate for current fluctuations, load controlled circuit apparatus comprising a comparator connected to the load for fixing a reference voltage which is determined by a component of the maximum compensated load voltage prior to voltage change for comparison with a voltage which is determined by subsequent compensated load voltage values, percentage means for fixing the percentage of voltage change effective to actuate said apparatus, and power means effective on change of comparator voltage to the set percentage value to operate said apparatus.

2. In a system of power supply control including a power source and a load unit receiving power from said source and subject to voltage change, load controlled circuit apparatus comprising a comparator connected to the load for fixing a component of the load voltage prior to voltage change for comparison with subsequent load voltage values, percentage means for fixing the percentage of voltage change effective to actuate said apparatus, and power means effective on change of comparator voltage to the set percentage value to operate said apparatus, said percentage means comprising a linear potential divider, an electrical bridge connected to the divider normally underbalanced to prevent load control actuation, but becoming overbalanced to cause said apparatus actuation on development of a voltage change in said comparator.

3. In a system of power supply control includ-

ing a power source and a load unit receiving power from said source and subject to voltage change, load controlled circuit apparatus comprising a comparator connected to the load for fixing a component of the load voltage prior to voltage change for comparison with subsequent load voltage values, percentage means for fixing the percentage of voltage change effective to actuate said apparatus, and power means effective on change of comparator voltage to the set percentage value to operate said apparatus, said percentage means comprising a linear potential divider, an electrical bridge connected to the divider normally underbalanced to prevent load control actuation, but becoming overbalanced to cause said apparatus actuation on development of a voltage change in said comparator, and means for determination of the setting of the potential divider and the underbalance of said bridge.

4. In an electrical system including a power source and load, percentage control apparatus functioning on load voltage change comprising a voltage divider having linear change characteristics, a bridge circuit connected to said divider, and power means actuated by said bridge circuit, said bridge circuit comprising two parallelly connected units of a resistor and an electronic vacuum tube having a control grid connected in series, a source of power connected to the junction points between the resistors and between the tubes, power actuating means connected to the junction points between each resistor and tube, and means connected to the control grid of one of said tubes for maintaining a component of load voltage value existing prior to voltage change, the control grid of the other tube having connection to the load circuit and variable therewith.

5. In an electrical circuit subject to voltage change, apparatus for establishing the initial voltage existing prior to voltage change, and utilizing the change from this initial voltage to operate power means, comprising a bridge having two electronic tubes and two resistors connected in series with in-power connections between each resistor and between each tube and out-power connections between each tube and resistor, an element connected to the grid of one of said tubes for fixing the prechange current voltage, and a connection between the control grid of the other tube and said circuit, whereby prior to circuit voltage change the bridge is unbalanced on a given bridge polarity, but on circuit voltage change is unbalanced on a reversed bridge polarity to actuate said power means.

6. In an electrical circuit subject to voltage change, apparatus for establishing the initial voltage existing prior to voltage change, and utilizing the change from this initial voltage to operate power means, comprising a bridge having two electronic tubes and two resistors connected in series with input power connections between each resistor and between each tube and output power connections between each tube and resistor, an element connected to the grid of one of said tubes for fixing the prechange current voltage, and a connection between the control grid of the other tube and said circuit, whereby prior to circuit voltage change the bridge is unbalanced on a given bridge polarity, but on circuit voltage change is unbalanced on a reversed bridge polarity to actuate said power means, and means for unbalancing said bridge prior to said voltage change.

7. In a system of power supply control includ-

ing a power source and a load unit receiving power from said source and subject to voltage change, load controlled circuital apparatus comprising a compensator for correcting for current change in said source power, a comparator connected to the load for fixing a component of the load voltage prior to voltage change for comparison with subsequent load voltage values, percentage means for fixing the percentage of voltage change effective to actuate said apparatus, and power means effective on change of comparator voltage to the set percentage value to operate said apparatus.

8. In a system including a variable alternating current power supply and a load, a circuit for delivering a rectified and compensated voltage component of said load, comprising means for rectifying a component of the load voltage, means for rectifying a component of the load current, means for balancing said variable current component with a fixed opposed voltage element, a grid controlled electronic tube having an effective resistance dependent on the differential voltage of the variable current component and fixed voltage, and means for connecting said tube to said rectified load voltage component circuit to increase the effective resistance of said circuit on load current drop and to decrease the effective resistance on load current increase whereby compensation of current change in said load circuit is secured in the rectified load voltage component circuit.

9. In a system of power supply control, a power source, a load unit receiving power from said source and subject to voltage change, and load controlled means connected to the load unit for changing the magnitude of power supply, said load control means comprising a translating circuit connected to the load unit for amplifying and rectifying current voltage at said load, a comparator device for fixing a maximum pre-change voltage component as applied to said load and comparing this voltage with the load voltage component on load voltage change, and bridge means balanced for cut-off prior to load voltage change and balanced for power supply after load voltage change.

10. In a system of power supply control including a power source and a load unit receiving power from said source and subject to voltage change, means for rectifying and filtering the voltage across the load, load controlled circuital apparatus comprising a compensator for correcting for current change in said source power, a comparator connected to the load for fixing a component of the load voltage prior to voltage change for comparison with subsequent load voltage values, means for reducing the filter charge lag, percentage means for fixing the percentage of voltage change effective to actuate said apparatus, and power means effective on change of comparator voltage to the said percentage values to operate said apparatus.

11. In a system of power supply control, in combination, a power supply source, a load unit receiving power from said source in separate periods, the load unit being subject to different resistance and voltage conditions for different periods and also subject to relatively sudden voltage change during each period, signal means responsive to the voltage across the load, means for compensating the load voltage signal for fluctuating current conditions, means for fixing for each period a proportional charge which is determined by the load voltage before change,

means for selectively varying the proportion of said charge, and electrical comparator means responsive conjointly to said fixed proportional charge and to a charge which is determined by the load voltage after change for furnishing a control impulse.

12. In a system of power supply control, in combination, a power supply source, a load unit receiving power from said source in separate periods, the load unit being subject to different resistance and voltage conditions for different periods and also subject to a relatively sudden voltage change during each period, signal means responsive to the voltage across the load, means for fixing for each period a proportional charge which is determined proportionally according to an extreme value of the voltage before change, and electronic comparator means responsive conjointly to said fixed proportional charge and to a charge which is determined by the load voltage after change for furnishing a control impulse, said electronic comparator means including paired tubes which maintain an unbalanced condition prior to period voltage change but balanced after voltage change.

13. In a system of power supply control, in combination, a power supply source, a load unit receiving power from said source in separate periods, the load unit being subject to different resistance and voltage conditions for different periods and also subject to a relatively sudden voltage change during each period, signal means responsive to the voltage across the load, means for fixing for each period a proportional charge which is determined proportionally according to an extreme value of the voltage before change, and electronic comparator means responsive conjointly to said fixed proportional charge and to a charge which is determined by the load voltage after change for furnishing a control impulse, said electronic comparator means including paired vacuum grid tubes and a gas grid tube, the vacuum tubes respectively influencing the gas tube according to proportional and full voltage conditions at the load and causing it to fire at a predetermined comparative condition for pre-change and post-change load voltage conditions.

14. In a system for power supply control, in combination, a power supply source, a load unit receiving power from said source and being subject to voltage variation across the load, signal means responsive to voltage across the load, said signal means including conductors which are subject to voltage distortion at the load, means for compensating for said voltage distortion, means for fixing a proportional charge which is determined by corrected load signal voltage before voltage change, and comparator means responsive conjointly to said proportional charge before voltage change and to a charge which is determined by the load voltage after change for furnishing a control impulse.

15. In a system for power supply control, in combination, a power supply source, a load unit receiving power from said source and being subject to voltage variation across the load, signal means responsive to voltage across the load, said signal means including conductors which are subject to voltage distortion at the load, means for compensating for said voltage distortion, means for fixing a proportional charge which is determined by corrected load signal voltage before voltage change, and comparator means responsive conjointly to said proportional charge before voltage change and to a charge which is deter-

mined by the load voltage after change for furnishing a control impulse, said compensating means including an induction coil in a voltage signal conductor.

16. In a system for power supply control, in combination, a power supply source, a load unit receiving power from said source and being subject to voltage variation across the load, signal means responsive to voltage across the load, said signal means including conductors which are subject to voltage distortion at the load, means for compensating for said voltage distortion, means for fixing a proportional charge which is determined by corrected load signal voltage before voltage change, and comparator means responsive conjointly to said proportional charge before voltage change and to a charge which is determined by the load voltage after change for furnishing a control impulse, said compensating means including a variable induction in the voltage signal circuit.

17. In a system of power supply control, in combination, a power supply source, a load unit receiving power from said source in separate periods, the load unit being subject to different resistance and voltage conditions for different periods and also subject to relatively sudden voltage change during each period, signal means responsive to the voltage across the load, means for compensating the load voltage signal for changed current conditions, means for fixing for each period a reference charge which is determined by the load voltage before change, electrical comparator means responsive conjointly to said fixed charge and to a charge which is determined by the load voltage after change for furnishing a control impulse when said last-mentioned charge attains a predetermined ratio with respect to said first-mentioned charge, and means for adjusting the predetermined ratio at which said control impulse is furnished.

18. In a system of power supply control for a welder, in combination, a power supply source, a welding load unit receiving power from said source in separate periods, the load unit being subject to different resistance and voltage conditions for different weld periods and also subject to relatively sudden voltage change during each weld period, signal means responsive to the voltage across the load, means for compensating the load voltage signal for changed current conditions, means for fixing for each period a reference charge which is determined by the load voltage before change, electrical comparator means responsive conjointly to said fixed charge and to a charge which is determined by the load voltage after change for furnishing a control impulse when said last-mentioned charge attains a predetermined ratio with respect to said first-mentioned charge, and means for adjusting the predetermined ratio at which said control impulse is furnished.
